The ornamental design for a display screen with icon for a vehicle monitoring apparatus, as shown and described.

DESCRIPTION

FIG. 1 is a front view of a display screen with icon for a vehicle monitoring apparatus showing our new design; FIG. 2 is a rear view thereof;

FIG. 3 is a top plan view thereof;

FIG. 4 is a bottom plan view thereof;

FIG. 5 is a right side view thereof, the left side view being a mirror image of FIG. 5;

FIG. 6 is an enlarged view showing a portion of FIG. 1 defined by line 6-6; and,

FIG. 7 is a front view showing the article in use.

The features shown in broken lines in the drawings depict environmental subject matter only and form no part of the claimed design. The dashed-dotted lines in FIGS. 1, 6 and 7 denote the boundary of the claim and form no part of the claimed design.
